TELEPHONE SYSTEM

Henry Hovland, Williston Park, N. Y., assignor to
 Bell Telephone Laboratories, Incorporated,
 New York, N. Y., a corporation of New York

Application October 16, 1940, Serial No. 361,365

16 Claims. (Cl. 179—18)

This invention relates to telephone systems and particularly to systems comprising subscriber controlled automatic switches for establishing connections between calling and called subscribers' stations.

Objects of the invention are an increase in the flexibility and efficiency of automatic switching equipments in dial telephone systems, and an improvement in the supervisory facilities of such systems.

It is usual in automatic telephone systems comprising a main and a branch office to provide switching selector repeaters in the branch office for selecting a trunk to the main office, for repeating all dial impulses over the selected trunk to the main office on calls to subscribers in the main office or other offices of the system, and for repeating dial impulses over the selected trunk to the main office on calls to subscribers in the branch office until as many digits have been dialed as are needed to determine that the called subscriber is located in the branch office, the trunk to the main office being released as soon as these digits have been dialed and the succeeding trains of dial impulses being effective to complete the desired connection through switches in the branch office. Among the patents disclosing branch office systems and switching selector repeaters are the patent to E. Jacobsen No. 1,537,306, May 12, 1925, and patents to H. Hovland No. 1,799,796, April 7, 1931, and No. 2,025,389, December 24, 1935.

According to the invention, an improved switching selector repeater is provided in a branch office of an automatic telephone system, the selector repeater having various new and novel features. One of the features is a circuit arrangement whereby the selector switch of a branch office selector repeater absorbs the last digit of the branch office code if this digit is a particular numerical value, or one of certain numerical values, and immediately hunts for an idle trunk in the corresponding level of its bank; but does not absorb the last digit of the branch office code, if the last digit is some other numerical value. This arrangement enables the connection of trunks to different orders of local switches in different levels of the bank of the selector of a selector repeater, thereby minimizing the number of local selector switches required.

A second feature of the invention is a branch office selector repeater arranged to absorb a digit of local or branch office subscribers' numbers after release of the selected trunk to the main

office on a call to a subscriber in the branch office.

Another feature is a branch office selector repeater arranged to automatically release the selected trunk to the main office in case no dial impulses are received within a predetermined interval of time, such for instance as twenty-four seconds.

Another feature is a branch office selector repeater arranged to release the line finder through which it is connected to a calling line within a predetermined interval, for instance two minutes, after the selected trunk to the main office is released due to a permanent signal condition.

Another feature is a branch office selector repeater arranged to operate a line lock-out relay on calls from lines equipped with such relays in case no dial impulses are received from the calling line within a predetermined interval of time, for instance two minutes.

Another feature is a branch office selector repeater arranged to deny to restricted service subscribers access to main office trunks and access to trunks in any desired level of the selector, the restricted service subscribers' lines being connected to one or more particular subgroups in the banks of the line finders through which the lines are connected to selector repeaters.

Another feature is a branch office selector repeater arranged to route calls to the main office through the non-numerical trunking switch and to route calls to another central office through a level of the numerical selector switch in response to the dialing of two digits.

Another feature is a branch office selector repeater arranged to route calls to an operator in response to the dialing of either an ~~11~~X code or an ~~X1~~ code, the letter X in each case representing a digit of any numerical value.

These and other features of the invention are embodied in the telephone system represented schematically in the drawings which form a part of this specification; and a clear and complete understanding of the invention will be facilitated by considering the system and the selector repeater circuits shown in the drawings. The invention is, however, not limited in its application to the particular system shown but is generally applicable to any system comprising automatic main and branch offices.

Referring to the drawings,

Fig. 1 shows in a branch office, subscribers' stations A and B, lines L1 and L2, line circuits

LC1 and LC2, a line finder LF and a connector BC1;

Figs. 2 and 3 show a branch office selector repeater SR1;

Figs. 4 and 5 show a branch office selector repeater SR2;

Fig. 6 shows permanent signal timing apparatus TA and miscellaneous alarm and register apparatus MA in the branch office;

Fig. 7 shows an intermediate local selector BS3, a service code selector SCS, connectors BC2 and BC3, and subscribers' stations X and Y, all in the branch office;

Figs. 8, 9 and 10 show various trunking and numbering schemes which may obtain in a main and branch office system; and

Figs. 11 and 12 show the relative positions in which Figs. 1 to 7 are to be placed to form operative arrangements.

The subscribers' stations are of the type employed in common battery telephone exchanges and each includes a dial or other impulse sender for use in controlling the switches through which desired connections are established. The line circuits LC1 and LC2 and the line-finder circuit LF are similar to those disclosed in the patent to T. L. Dimond No. 2,210,068 granted Aug. 6, 1940. The line circuit LC1 includes a line relay 14 and a permanent signal lock-out relay 16. The line circuit LC2 is similar to the line circuit LC1 except that it is not provided with a permanent signal lock-out relay.

The line-finder, selector and connector switches are of the well-known two-motion step-by-step type. Reference may be had to pages 53 to 65, inclusive, of the second edition of "Automatic Telephony" by Smith and Campbell for a description of the structure of such switches and their operation when used as selectors and connectors. Reference may be had to the patent to R. L. Stokeley, No. 1,799,654, granted April 7, 1931, and to the aforementioned patent to T. L. Dimond for a description of the operation of such switches when used as line finders. Each of the line finder, selector and connector switches LF, SCS, BC1, BC2 and BC3 is represented in Figs. 1 and 7 by a set of brushes and one, two, or three sets of terminals, all magnets, relays and other associated apparatus being omitted; except that the line finder LF is further represented by three sets of contact springs 25, 26 and 28 and release magnet 29. The numerical selector switches BS1 and BS2 of the selector repeaters SR1 and SR2 and the branch office selector BS3 are shown in detail. The bank of each of selectors BS1 and BS2 is represented by four sets of terminals. The terminals 71 and 271 represent the first levels in the bank of selectors BS1 and BS2; terminals 72 and 272 represent levels connected directly to connectors; terminal 73 represents a level of the bank of selector BS1 connected to third selectors BS3; terminals 273 represent a level of the bank of selector BS2 connected to trunks to another office; and terminals 74 and 274 represent the tenth levels of the banks of selectors BS1 and BS2.

The selector repeater SR1 shown in Figs. 2 and 3 includes a trunk hunting switch TS1 comprising brushes 91, 92 and 93 and a stepping magnet 90, a numerical selector switch BS1 comprising brushes 61, 62, 63 and 64, commutator brush 65 and vertical commutator 66, vertical off-normal springs 67, 11th rotary step springs 68, normal post springs 69 and 70, vertical stepping magnet 75, rotary stepping magnet 76 and

release magnet 77. The selector repeater SR1 further includes a line relay 47, impulse repeating relay 45, switching relay 40 and other control relays as hereinafter described. Two terminal strips 78 and 79 are provided for interconnecting the segments of commutator 66 and the windings and contacts of control relays 80 to 86, inclusive, 88 and 89 as required for any particular trunking arrangement and numbering scheme. There are sixteen terminals in each of the terminal strips 78 and 79, which terminals are referred to in the detailed description as being numbered from 1 to 16, beginning at the bottom of each strip.

The system represented in Figs. 1, 2, 3, 6 and 7 conforms to the trunking plan shown in Fig. 8. Referring to Fig. 8, the trunking arrangement is designed to provide for a total of 9,700 five-digit subscribers' numbers in a main office and a branch office. Numbers from 80000 to 81999 and 84000 to 89999 are assigned to the main office; numbers from 82000 to 82999 and 83300 to 83999 are assigned to the branch office; and it requires a maximum of two digits to determine whether a called number is located in the branch or in the main office. The first digit of the main and branch office numbers could be any desired digit other than 0 to 1. The digit 0 is used for calling an operator and the digit 1 is employed for special service codes comprising three digits, the first two of which are the digits 11.

In the branch office, the subscribers' lines terminate in line-finder switches, such as LF, and in the banks of connector switches, such as BC. The line finders are used to establish connections with lines when calling, and the connectors with lines when called. The station A represents a calling station and the stations X and Y represent called stations. Each line finder is permanently associated with a selector repeater SR which includes a numerical selector switch BS and a non-numerical trunk hunting switch TS. The terminals in the banks of the trunk hunting switches connect to trunks such as T1 leading to the main office and terminating in incoming selectors such as IS1. The terminals of the first level of the bank of the selector switches BS of the selector repeaters SR are connected to service code selectors. The terminals of the second level are connected to third selectors such as BS3; the terminals of the third to ninth levels are connected to connector switches; and the terminals of the tenth or zero level of the bank are connected to trunks leading to an operator's position.

In the main office, the subscribers' lines are in like manner terminated in the banks of line-finder switches (none being shown) and in the banks of connectors such as C. The station Z represents a subscriber's station to which the connector C has access. In addition to the incoming first selectors such as IS1 for extending calls originated by subscribers in the branch office, local first selectors (not shown) are provided for use in extending calls originated by subscribers in the main office. The first selectors, both incoming and local, have access to the same or similar groups of trunks. Terminals of the first levels of the incoming selectors such as IS1 are connected to auxiliary first selectors for absorbing a preliminary impulse. The terminals of levels 2 to 7, inclusive, and level 9 may be connected to trunks leading to other offices. The terminals in level 8 are connected to second selectors such as S2 and the terminals

in the tenth or zero level of the incoming first selectors are not used. The terminals in the second and third levels of the second selectors S2 are connected to trunks leading to incoming selectors in the branch office for use in completing calls from main office subscribers to subscribers in the branch office. The terminals in the other levels of the second selectors are connected to third selectors such as S3. The terminals of all levels of the third selectors S3 are connected to connector switches C having access to subscribers' lines.

When the line-finder switch LF associated with the selector repeater SR1 of Figs. 2 and 3 starts to hunt for a calling line, the trunk hunting switch TS1 starts to hunt for an idle trunk to the main office. When the calling subscriber dials a first digit, the dial impulses are repeated over the trunk to the main office and the brushes of selector BS1 are advanced to a corresponding level. If all of the trunks to the main office are busy, the selector BS1 responds to the first digit and if the called station is in the branch office the call will be completed; but if the called station is not in the branch office, a busy tone is transmitted to the calling station. If the first digit is 0, the selector BS1 hunts in the tenth level for an idle trunk to an operator; and the trunk to the main office is released. If the first digit is 1, the brushes of selector BS1 are stepped up to the first level and are then restored to normal; if the next digit is any other than 1, the operation is the same as if no preliminary digit had been received; but if the second digit is also the digit 1, the brushes are again stepped up to the first level and rotated therein to select an idle service code selector SCS. If the first digit dialed is any other than 0, 1 or 8, the brushes of selector BS1 are advanced to the corresponding level, and remain in this position without trunk hunting while succeeding trains of dial impulses are repeated over the trunk to the main office to control the completion of the desired connection. If the first digit dialed is 8, the called station is either in the branch or in the main office; and the brushes are advanced to level 8, and are then restored to normal. When the second digit is dialed, the impulses are repeated over the trunk to the main office and the brushes are again advanced to the corresponding level. If the second digit is any other than 2 or 3, the called station is in the main office, the brushes of selector BS1 are held opposite the selected level without trunk hunting, and succeeding trains of dial impulses are repeated over the trunk to the main office to control the selector and connector switches through which connection with the called station in the main office is completed. If the second digit is the digit 2, the trunk to the main office is released and the brushes are advanced in the second level to select an idle selector BS3, the impulses created by the dialing of the third, fourth and fifth digits being transmitted through the brushes of selector BS1 to control the operation of the selector BS3 and a connector BC3 to complete connection with the called station. If the second digit is the digit 3, the brushes of selector BS1 are again returned to normal and the trunk to the main office is released. When the third digit is dialed the brushes of selector BS1 are advanced to the corresponding one of levels 3, 4, 5, 6, 7, 8 or 9 and advanced in this level to select an idle connector BC2, the impulses created by the dialing of the fourth and fifth digits being repeated through the brushes of selector BS1 to

control the connector to complete connection with the called station. If the brushes of selector BS1 are advanced in any level to select an unguarded set of terminals and all of the sets are guarded against seizure, the brushes are advanced to the 11th rotary position in which a busy tone is transmitted to the calling station. If the calling station is a restricted service station, the actuation of the springs 25 of the line finder so indicates; and, if the first digit dialed is any other than 0, 1 or 8, the brushes of selector BS1 are advanced in the corresponding level to the 11th rotary position and a busy tone is transmitted to the calling station. In some trunking arrangements in which the selector repeater SR1 may be used, trunks to another office may be connected to a level of the selector BS1; and, when a restricted service subscriber calls this other office, the operation of normal post springs 70 effects the advance of the brushes to the 11th rotary position to effect the transmission of a busy signal to the calling station.

When the selector repeater SR1 is connected to a calling station, it starts the operation of a common permanent signal timing apparatus TA. If all of the subscribers' lines are arranged for permanent signal lock-out, and if no dial impulses are received within twenty-four seconds, the line finder is released, the trunk to the main office is released, and the permanent signal lock-out relay in the calling subscriber's line circuit is operated to prevent connection of the line to another selector repeater. If some but not all subscribers' lines are arranged for permanent signal lock-out, the trunk to the main office is released if no dial impulses are received within twenty-four seconds after connection of a calling line to the selector repeater; and, after a further interval of two minutes, the line finder is released and the permanent signal lock-out relay of the calling line is operated in case the call is from a line including such a relay. If the calling line does not include a lock-out relay, the line will again be connected to a selector repeater. If none of the lines is arranged for permanent signal lock-out, and if no dial impulses are received within twenty-four seconds after a calling line is connected to the selector repeater, the trunk to the main office is released; but the selector repeater SR1 is held until a further predetermined interval has elapsed; whereupon a permanent signal alarm is operated as hereinafter described in connection with a permanent signal condition existing on a line connected to selector repeater SR2.

The timing apparatus TA comprises means for measuring intervals of from two to four minutes, means for measuring intervals of from twenty to thirty minutes, means for measuring intervals of approximately twenty-four seconds, and means for releasing selector repeaters to which are connected lines on which permanent calling conditions exist.

The means for measuring intervals of two to four minutes comprises relays 121, 122 and 123. When these relays are not in use, ground is connected through back contacts of relays 121 and 123 to conductor 125. When ground is connected to start conductor 120, relay 121 operates disconnecting ground from conductor 125. The operation of relay 121 causes the operation of relay 122, from two to four minutes later. The operation of relay 122 causes the operation of relay 123. The operation of relay 123 causes the release of relay 121 and connects ground to con-

ductor 124. The release of relay 121 causes the release of relay 122; the release of relay 122 causes the release of relay 123; and the release of relay 123 disconnects ground from conductor 124, connects ground to conductor 125, and connects relay 121 to the start conductor 120. This cycle of operations is repeated as long as ground is connected to start conductor 120. Relay 121 is slow in operating to insure the connection of ground to conductor 125 for a required interval of time, and relay 123 is slow in releasing to insure the disconnection of ground from conductor 124 for a required interval of time.

The means for measuring intervals of twenty to thirty minutes comprises relays 151, 152 and 153 which, upon connection to ground to start conductor 150, operate to connect ground to conductor 155 for a short interval once every twenty to thirty minutes and to disconnect ground from conductor 154 for a short interval once every twenty to thirty minutes.

The means for measuring intervals of approximately twenty-four seconds comprises timing relays 131, 132 and 133 and a start relay 134. Upon connection of ground to start conductor 130, relay 134 operates closing a circuit for operating relay 131. Relay 131 closes a circuit for operating relay 135 to disconnect battery from conductor 103 and other similar conductors. Relay 131 also closes the circuit for operating relay 132; and, twenty-four to twenty-eight seconds later, relay 132 operates. Relay 132 closes a circuit for operating relay 133. Relay 133 closes a holding circuit for relay 135, causes the release of relay 134, and connects ground to conductor 105. The release of relay 134 causes the successive release of relays 131, 132, 133 and 135. The release of relay 133 reconnects start relay 134 to conductor 130; and the above-described cycle of operations is repeated as long as ground is connected to conductor 130. By the connection of ground to conductor 105, the release of main office trunks is effected in selector repeaters connected to lines on which a permanent signal condition exists.

The means for releasing selector repeaters connected to lines in a permanent calling condition comprises relays 142 to 145, inclusive, the operation of which is hereinafter described in detail.

Referring now to the detailed circuits disclosed in Figs. 1, 2, 3, 6 and 7 arranged according to Fig. 11, assume that a call is originated at station A. Upon removal of the receiver by the calling subscriber, a circuit is closed for operating the line relay 14 of line circuit LC1. This circuit is traced from battery through the middle and upper windings of relay 14, inner upper back contact of relay 14, conductor 12 of line L1, through the telephone instrument at station A, conductor 11 of line L1, inner lower back contact and lower winding of relay 14 to ground. Relay 14 is thereby energized sufficiently to close its outer front contacts without affecting its remaining contacts. At its upper front contact, relay 14 closes a circuit including the inner lower back contact of relay 16, the outer upper back contact of relay 14, and conductor 15 for operating the start relay 18, relay 18 being thereupon effective to start the operation of an idle line finder LF to search for the calling line as described in detail in the aforementioned patent to T. L. Dimond. At its outer lower front contact, relay 14 closes a connection from its middle winding, through back contacts of relay 16 and conductor 13, to the test terminals of the sets of terminals in the banks of the line-finder switches having access to the line

51. As soon as a line finder LF starts searching for the calling line, ground potential is connected to conductor 33, thence through the upper back contact of relay 85, a lower back contact of relay 57 and the outer back contact of relay 58 to the winding of relay 55, thereby operating relay 55 of the selector repeater SR1 to start the trunk hunting operation of switch TS1 as hereinafter described. When the brushes 20 of the line finder LF connect with the terminals 21 to which the calling line is connected, ground potential is connected through the lower brush to conductor 13 to fully energize the middle winding of relay 14, and a circuit is closed for operating the line relay 47 of the associated selector repeater SR1. The energization of the middle winding of relay 14 upon connection of ground potential to conductor 13 completely operates relay 14, thereby disconnecting the line conductors 11 and 12 from the windings of relay 14 and disconnecting ground potential from conductor 15 so as to release start relay 18 if there is at this time no other calling line in this same line finder group awaiting extension to a selector repeater. The circuit for operating the line relay 47 is traced from battery through the lower winding of relay 47, the upper back contact of relay 44, a lower back contact of relay 40, conductor 32, the middle brush of line finder LF, conductor 12, through station A, conductor 11, upper brush of line finder LF, conductor 31, an upper back contact of relay 40, inner lower back contact of relay 44, upper winding of relay 47, upper back contact of the 11th rotary step springs 68, inner lower back contact of relay 43, inner lower back contact of relay 57, through the primary winding of the dial tone transformer 58 to ground. Relay 47 closes circuits traced from ground through a lower back contact of relay 40 and the lower front contact 49 of relay 47 for operating relays 42 and 53, the circuit for operating relay 53 further including the lower back contact of release magnet 77 and the back contact of the vertical off-normal springs 67. At its outer upper front contact, relay 42 connects ground to conductor 33 to hold the line finder LF and relay 14 in usual manner, and to maintain the operation of relay 55 in case the switch TS1 has not completed its trunk hunting operation. Relay 42 also closes a circuit for operating the start relay 39 of the ringing and tone supply apparatus RA.

55. The aforementioned operation of relay 55 connects the winding and interrupter contact of stepping magnet 90 of trunk hunting switch TS1, through the outer upper front contact of relay 55, inner back contact of relay 58, and through the test brush 93 of switch TS1, to the test conductor of the trunk connected to the terminals with which the brushes of switch TS1 are then in engagement. Relay 55 also closes a circuit from ground through its outer lower front contact and the winding of relay 58, in series with the interrupter contact and winding of stepping magnet 90. If the trunk connected to the terminals then engaged by the brushes of switch TS1 is busy, the test conductor is connected to ground thereby preventing the operation of relay 58 and operating magnet 90. Magnet 90 opens its own operating circuit, and its release advances the brushes of switch TS1 to the next set of terminals. The operation and release of magnet 90 is repeated to advance the brushes step by step until an unguarded set of brushes is encountered. If the trunk, connected to the terminals with which the brushes of switch TS1 is in engage-

ment when relay 55 operates, is idle, or as soon thereafter as the brushes are advanced into engagement with a set of terminals connected to an idle trunk, relay 50 is operatively energized in series with the stepping magnet 90. Since the stepping magnet 90 is marginal, it does not operate in series with relay 50; and, therefore, no further advance of the brushes occurs. Relay 50 connects ground to test brush 93 to guard the selected trunk to the main office against seizure by any other trunk hunting switch, closes a circuit for energizing the upper polarizing winding of relay 44, opens the operating circuit of relay 55 and closes a holding circuit for relay 55 through the lower back contact of relay 48; lower contact of the 11th rotary step springs 68, to ground at a front contact of relay 42. With both of relays 50 and 47 operated, a circuit is closed for operating relay 45. With relay 45 operated, the upper conductor of the selected trunk T to the main office is connected through brush 91, the upper front contact of relay 45, the outer lower front contact of relay 53, through resistor 54, to battery; and the lower conductor of the selected trunk T is connected through brush 92, the inner upper front contact of relay 50, the lower front contact of relay 45, the outer upper front contact of relay 53, through resistor 51, to ground. The connection of battery and ground to the conductors of the selected trunk T to the main office effects the operation of the line relay (not shown) of the incoming selector associated with the trunk T in the main office to prepare the incoming selector for response to dial impulses.

Dial tone is transmitted through the windings of transformer 58, and the upper winding of relay 47, to the calling station to indicate that the subscriber may start dialing. When the subscriber dials the first digit of a called subscriber's number, relay 47 is alternately released and reoperated as many times as there are units in the digit dialed. The release of relay 47, in response to the first impulse, connects ground through its back contact, the outer lower front contact of relay 42, lower back contacts of relays 49 and 43, to the winding of relay 57 and to the winding of the vertical stepping magnet 75. Relay 57 operates, locks to the ground on conductor 33, disconnects its winding from the impulse contact of relay 47, disconnects the dial tone transformer from the upper winding of relay 47, and connects ground potential directly to this winding. In case the calling subscriber starts to dial before a trunk to the main office has been selected, the operation of relay 57 causes the release of relay 55, thereby stopping the operation of trunk hunting switch TS1. The operation of vertical stepping magnet 75 raises the brushes 61, 62, 63 and 64 up to the first level of the terminal bank, the vertical off-normal springs 67 being actuated as soon as the shaft is moved out of its normal position. With vertical off-normal springs 67 actuated, the winding of the relay 53 is disconnected from the lower front contact of relay 47 and is connected through the middle front contact of springs 67 and a lower back contact of relay 44, in parallel with the vertical stepping magnet 75 under the control of the lower back contact of relay 47. When relay 47 reoperates at the end of the first impulse, magnet 75 releases; but relay 53 is a slow-to-release relay and it remains operated until all of the impulses in the train created by the dialing of the first digit have been received. Relay 42 is also slow in releasing and remains operated during the response of relay

47 to dial impulses. Each release and reoperation of relay 47 in response to succeeding impulses of the train created by the dialing of the first digit, causes the reoperation and release of stepping magnet 75, thereby advancing the brushes 61, 62, 63 and 64 to the level corresponding to the digit dialed. Each release of relay 47 further causes the release of relay 45 to disconnect battery and ground from the conductors of the trunk to the main office and to thereby repeat the dial impulses to the line relay of the incoming selector in the main office. At the end of the train of impulses corresponding to the first digit, relay 47 remains operated thereby causing the release of relay 53. The release of relay 53 disconnects battery and ground from the conductors of the trunk to the main office and closes a bridge across these conductors, this bridge being traced from brush 91 through the upper contact of relay 45, outer lower back contact of relay 53, lower winding of relay 44, upper back contact of relay 53, upper back contact of relay 48, inner upper front contact of relay 50, to brush 92 of switch TS1. The lower winding of relay 44 is thereby energized in series with the line relay of a second selector in the main office, the current through the winding of relay 44 being in the non-operating direction.

The normal post springs 69 are adjusted to be actuated on all levels; and the actuation of these springs, as soon as the brushes are stepped up to the first level of the bank, closes a circuit for operating relay 87. This circuit includes springs 69, the back contact of rotary stepping magnet 76, the upper back contact of relay 48, the inner lower front contact of relay 53, and the inner upper back contact of relay 43. Relay 87 locks through its lower front contact, the middle upper back contact of relay 43, the inner lower back contact of relay 40, conductor 33, to ground at a front contact of relay 42. Relay 87 prepares for the operation of the rotary stepping magnet 76 in case trunk hunting is required on the level selected in response to the first train of impulses.

Assume first that the call is to an operator, the first digit dialed being the digit 0. In this case, the brushes of selector BS1 are advanced to the tenth or zero level; and, when relay 53 releases, a circuit is closed for operating relay 86. This circuit is traced from the winding of relay 86, through the lower back contact of relay 81, the tenth terminal of commutator 66, brush 65, the lower back contact of relay 86, upper back contact of release magnet 77, inner lower back contact of relay 53, to ground at the inner upper back contact of relay 43. Relay 86 closes a locking circuit through its inner upper front contact before its operating circuit is opened at its lower back contact, the locking circuit including back contacts of relays 43 and 40, conductor 33, to ground at a front contact of relay 42. Relay 86 closes a circuit for operating the rotary stepping magnet 76. This circuit is traced from battery through the winding of magnet 76, the outer lower front contact of relay 86, back contacts of relays 83 and 84 in parallel, the upper front contact of relay 87, upper back contact of release magnet 77, inner lower back contact of relay 53, to ground at a back contact of relay 43. The operation of magnet 76 steps the brushes 61, 62, 63 and 64 into engagement with the first set of terminals in the tenth level and opens the locking circuit of relay 87. Relay 87 releases, thereby causing the release of magnet 76. If the trunk connected to the first set of terminals

is busy, the test brush 63 encounters a ground potential which is extended through the lower-most back contact of relay 40, the middle lower back contact of relay 43, upper back contact of relay 49, back contact of rotary stepping magnet 76, springs 69, to the winding of relay 87, thereby causing the reoperation of relay 87. Relay 87 again closes the circuit for operating the stepping magnet 76; and the brushes are advanced into engagement with the next set of terminals. Relay 87 and magnet 76 are thus effective to continue the advance of the brushes until a set of terminals, connected to an idle trunk circuit OT, is encountered. If all the terminals in the level test busy, the brushes are advanced to the 11th rotary position in which contact springs 68 are actuated to connect the busy tone source BT of apparatus MA to the upper winding of relay 47, thereby transmitting an all-trunks-busy tone to the calling subscriber. If and when an idle set of terminals is encountered, there is no ground potential connected to the terminal engaged by test brush 63 and relay 49 is operated, the circuit for operating relay 49 is traced from battery through the winding of relay 87, springs 69, back contact of rotary stepping magnet 76, winding of relay 49, inner lower front contact of relay 86, lower back contact of the 11th rotary step springs 68, to ground at a front contact of relay 42. Relay 87 is marginal and does not operate in series with the winding of relay 49. The operation of relay 49 opens the short circuit around resistor 37, thereby connecting this resistor in series with the winding of the vertical stepping magnet 75, to prevent the further operation of magnet 75. Relay 49 closes a circuit from ground at the middle upper front contact of relay 42, through the upper back contact of relay 83 and the lower front contact of relay 49, for operatively energizing the upper winding of relay 49 in series with the winding of relay 41. The operation of relay 41 may momentarily close a circuit for energizing relay 43; but relay 43 is slow in operating and, as soon as relay 40 operates, the circuit for energizing relay 43 is opened. Relay 40 locks through its lower winding to ground on conductor 33, disconnects the windings of relay 47 from conductors 31 and 32, and connects conductors 31, 32, 33 and 34 through brushes 61, 62, 63 and 64 to the selected trunk circuit OT. The operation of relay 40 causes the release of relays 47, 86, 42, 45, 49, 55, 50 and 41. The calling line is thus connected through conductors 31 and 32, brushes 61 and 62 and terminals 74, to the trunk circuit OT which is effective in usual manner to connect a holding ground potential to the terminal engaged by test brush 63, thence through brush 63 to conductor 33, to hold relays 40 and 57 of the selector repeater, to hold the line finder LF, and to hold the combined line and cut-off relay 14 of the calling line. Reference may be had to the patent of R. B. Buchanan et al., No. 2,233,282, granted Feb. 25, 1941, for description of a trunk circuit associated with a trunk to an operator. A class of calling subscriber indication is given in a circuit including the level contacts 26 of line finder LF, conductor 34, a front contact of relay 40, outer lower back contact of relay 83, brush 64 and the terminal with which it is in engagement. One class of calling line is indicated by the connection of ground through a resistance 27 to conductor 34 as shown in Fig. 1; another class by the connection of ground directly to conductor 34; and a third class by the lack of connection of ground to conductor 34.

The release of relays 45 and 59 opens the loop across the conductors of the trunk to the main office, thereby effecting the release of the associated incoming selector in the main office. The main office trunk is not released until after the selector repeater has found an idle trunk to the operator or until the brushes have advanced to the 11th rotary step position if all of the trunks are busy. Since the operator's trunks are connected to the tenth level of the selectors of branch office selector repeaters, the terminals in the tenth level of the incoming selectors associated in the main office with trunks from the branch office are not connected to operators' trunks; but these incoming selectors trunk hunt in the tenth level and therefore the test terminals in this level should be connected to ground to prevent the selection of any of these terminals. Otherwise the incoming selector might immediately begin to release before the selector in the branch office had found an idle trunk to the operator; and the line relay of the incoming selector might then be reoperated during release and thereby jamb the wipers.

When the call is released by the calling subscriber and by the operator, the holding ground potential is disconnected from the terminal engaged by test brush 63, thereby causing the release of relays 40 and 57 of the selector repeater SRI, and the release of the combined line and cut-off relay 14. The release of relay 40 closes a circuit including back contacts of relays 40, 47 and 42 for operating the release magnet 77 of selector BS1 and the release magnet 29 of line finder LF. The brushes of the selector BS1 and line finder LF are thereby restored to normal. When the shaft of selector BS1 reaches normal, the contact springs 67 are restored to normal, causing the release of magnet 77; and when the shaft of line finder LF reaches normal, the contact springs 29 are restored to normal, releasing magnet 29.

Assume next that the first digit dialed is a digit other than 0, 1 or 8, the called subscriber being located in some office other than the main or branch offices, and the call being completed over a trunk to the main office. When relay 53 releases after the reoperation of relay 41 at the end of the last impulse in the train, it closes a circuit for operating relay 43. If the first digit is 4, 5, 6, 7 or 9, this circuit is traced from battery through the winding of relay 43, upper back contact of relay 88, terminal 13 and one of terminals 4, 5, 6, 7 and 9 of terminal strip 79, the segment of commutator 65 with which brush 65 is in engagement, the lower back contact of relay 86, back contact of release magnet 77, inner lower back contact of relay 53, to ground at a back contact of relay 43. If the first digit is 2, this circuit includes the upper back contact of relay 88, the outer lower back contact of relay 84, terminals 14 and 2 of terminal strip 79, and segment 2 of commutator 66. If the first digit is 3, this circuit includes the upper back contact of relay 88, terminal 13 of terminal strip 79, terminal 16 of terminal strip 78, lower back contact of relay 82, terminal 15 of terminal strip 78, terminal 3 of terminal strip 79, and segment 3 of commutator 66. Relay 43 locks through its upper front contact, the inner lower back contact of relay 40, conductor 33, to ground at a front contact of relay 42, this locking circuit being closed before the operating circuit is opened. The operation of relay 43 causes the release of the rotary stepping relay 87, opens the short cir-

cuit around resistor 37 so as to prevent further operation of the vertical stepping magnet 75, and disconnects ground from the conductor leading to the winding of the start relay 39 of the ringing and tone apparatus RA.

If, on a call to be completed through the main office, all of the trunks to the main office are busy upon seizure of the selector repeater SR1, relay 55 is released due to the operation of relay 57; and, when relay 43 operates, busy tone is transmitted to the calling subscriber. To this end, the upper winding of relay 47 is connected through the upper back contact of the 11th rotary step springs 68, the lower front contact of relay 43, the inner back contact of relay 55, conductor 101, through the winding of relay 112 and the primary winding of the busy transformer BT to ground in the common miscellaneous alarm and register apparatus MA. Relay 112 operates, closing a circuit for operating relay 113; and relay 113 closes a circuit for operating the over-flow register 114. When the calling subscriber releases, relays 41, 45, 57, 42 and 43 are released. The release of relays 47 and 42 closes a circuit for operating the release magnet 77, thereby restoring the brushes of selector BS1 to normal.

If, on a call to be completed through the main office, an idle trunk to the main office is selected prior to the dialing of the first digit, relay 55 does not release when relay 57 operates, and the brushes of selector BS1 remain opposite the selected level without trunk hunting therein. The succeeding trains of impulses transmitted over the calling line are repeated over the trunk T to operate switches in the main and called offices to complete the desired connection. The talking connection includes back contacts of relay 40, front contacts of relay 57, front contacts of relays 57, 45 and 50, and condensers 59 and 60. When the connection is released by the calling subscriber, the release of relay 47 causes the release of relays 42, 57 and 45; and the release of relay 42 causes the release of relays 43, 55, of relay 42 causes the release of relays 43, 55, 50 and 14, the selector BS1 and line finder LF being restored to normal in the manner above described.

If the calling subscriber is a restricted service subscriber and the springs 25 of the line finder LF are actuated, the operation of relay 57 closes a circuit for operatively energizing the lower winding of relay 88. If then the first digit dialed indicates that a calling subscriber is located in an office other than the main or the branch office, the release of relay 53, after relay 47 reoperates at the end of the train of impulses, closes a circuit for operating relay 89. This circuit is traced from battery through the winding and back contact of relay 89, outer upper front contact of relay 88, terminals of terminal strips 79 and 78 as above described, segment of commutator 66 with which brush 65 is in engagement, lower back contact of relay 86, upper back contact of release magnet 77, inner lower back contact of relay 53, to ground at a back contact of relay 43. Since relay 88 has been contact of relay 43. Since relay 88 has been operated, relay 43 is normal. Relay 89 locks through its outer lower front contact, back contacts of relays 43 and 40, conductor 33, to ground at a front contact of relay 42. Relay 89 closes a circuit for operating relay 86 and connects ground through its upper front contact to test brush 63 to simulate a busy condition on all test terminals engaged by this brush. The rotary stepping magnet 76 is thereby operated to ad-

vance the brushes to the 11th rotary position. The operation of springs 68 disconnects ground from test brush 63 to prevent further stepping and connects the upper winding of relay 47 to the busy tone transformer BT in the miscellaneous alarm and register apparatus MA, to effect the transmission of a busy tone to the calling subscriber. In this manner calls from restricted subscribers to distant offices are prevented. When the calling subscriber releases the connection, the selector repeater and line finder are restored to normal as above described.

Assume next that the first digit dialed is the digit 8. In this case the called line is either in the main or branch office, but it cannot be definitely determined whether it is in the one or the other until the second digit has been dialed. When relay 53 releases after relay 47 operates at the end of the last impulse of the train, it closes a circuit for operating relay 84. This circuit is traced from battery through the winding of relay 84, inner upper back contact of relay 82, terminals 15 and 8 of terminal strip 79, terminal 8 of the vertical commutator 66, brush 65, thence to ground at the back contact of relay 43 as hereinbefore described. Relay 84 closes a locking circuit through its inner lower front contact, winding of relay 82, through back contacts of relays 43 and 40, conductor 33, to ground at a front contact of relay 42. Relay 82 is, however, short-circuited through the commutator brush 65 and does not operate until the operation of release magnet 77 opens this short circuit. Relay 84 closes a circuit for operating the release magnet 77. This circuit includes the lower front contact of springs 67, and the outer upper back contact of relay 82. The release magnet of the line finder is not energized at this time because the circuit for operating this magnet is not closed until the cut-through relay (not shown) of the line finder is released. Magnet 77 locks through the lower front contact of springs 67, the front contact of magnet 77, inner lower back contact of relay 53, to ground at a back contact of relay 43; causes the return of the brushes of selector S1 to normal; and opens the operating circuit of relay 84. When its operating circuit is opened, relay 84 is held operated in series with the winding of relay 82, and relay 82 operates in a circuit through back contacts of relays 43 and 40, conductor 33, to ground at a front contact of relay 42. When the shaft reaches normal, relay 87 releases, the vertical off-normal springs 67 are restored to normal, and the lower winding of relay 85 is operatively energized in series with the release magnet 77. This circuit includes the middle lower front contact of relay 57, the lower winding and inner lower back contact of relay 85, the front contact of magnet 77, thence as above described, to ground at a back contact of relay 43. Relay 85 locks through its upper winding and upper front contact under control of relay 42, the operating circuit being opened at its inner lower back contact to release the magnet 77. The aforementioned operation of relay 82 in series with the winding of relay 84 disconnects terminal 8 of commutator 66 from the winding of relay 84 and connects this terminal to terminal 11 of terminal strip 79 thence, through terminal 13 of terminal strip 79 and the upper back contact of relay 83, to the winding of relay 43. The impulses created by the dialing of the second digit cause the reoperation of the selector BS1; and these impulses are repeated over the main office trunk to operate a second selector in

the main office. If the second digit is any digit other than 2 or 3, the called line is in the main office; and the release of relay 53, after the last impulse of the train, closes a circuit for operating relay 43; or, if the call is from a restricted service subscriber and relay 88 has been operated, the release of relay 53 closes a circuit for operating relay 89 to effect the transmission of a busy tone to the calling station. The circuit for operating relay 43 is traced through the upper back contact of relay 88, terminal 13 of terminal strip 78, through the segment of commutator 66 with which the brush 65 is in engagement, lower back contact of relay 86, back contact of release magnet 77, through the inner lower back contact of relay 53, to ground at a back contact of relay 43. Relay 43 closes its locking circuit before its operating circuit is opened, inserts resistor 37 in series with the vertical stepping magnet 75 to prevent further operation of this magnet, releases relay 81, and disconnects ground from the start lead of the ringing and tone apparatus RA. The brushes of the selector remain opposite the selected level and the succeeding trains of dial impulses received from the calling line are repeated over the main office trunk to operate selector and connector switches in the main office to complete the connection to the called subscriber's line. The talking connection includes condensers 59 and 60 and the connection is under the control of the calling station, release being effected as above described.

If the second digit dialed after absorption of a first digit 8 is the digit 2, the release of relay 53, after the last impulse of the train, closes the above described circuit for operating relay 86; and relay 86 causes the advance of the brushes of selector BS1 in the second level to hunt for an idle trunk leading to a third selector BS3. When an unguarded set of terminals are engaged by the brushes, relay 49 operates but if all terminals are guarded, the brushes are advanced to the 11th rotary position and a busy tone is transmitted to the calling station. If relay 49 operates, it closes the circuit for operating relays 40 and 41. When relay 40 operates and locks as hereinbefore described, it causes the release of relays 83, 47, 42, 45, 50 and 55. The release of relay 50 opens the bridge across the trunk to the main office to effect the release of the switches in the main office.

Upon selection of a set of terminals connected to a branch office third selector BS3 and operation of relay 40, a circuit is closed for operating the line relay 171 of selector BS3. This circuit is traced from battery through the lower winding of relay 171, inner lower back contact of relay 174, brush 62, a front contact of relay 40, conductor 32, middle brush of line finder LF, conductor 12, through the calling subscriber's station, conductor 11, upper brush of line finder LF, conductor 31, a front contact of relay 40, brush 61, inner upper back contact of relay 174, upper winding of relay 171, to ground at a back contact of the 11th rotary step springs 186. Relay 171 closes a circuit for operating relay 172; and relay 172 connects ground, through conductor 170, to the terminal engaged by test brush 63, thereby maintaining a ground potential on conductor 33 to hold relays 40 and 57, to hold the line finder LF, and to hold the line and cut-off relay 14. When the calling subscriber dials the third digit of the called subscriber's number, relay 171 is alternately released and reoperated in response to each impulse. The release of relay

171 in response to the first impulse closes a circuit, which includes back contacts of relays 174 and 171, the lower front contact of relay 172, the winding of relay 173 and the winding of the vertical stepping magnet 177, for operating relay 173 and magnet 177. The operation of magnet 177 steps the brushes up to the first level of the terminal bank. When the shaft moves out of normal position, the vertical off-normal springs 185 are actuated, thereby closing a circuit from ground at the upper contact of relay 172 through the front contact of relay 173 and upper contact of springs 185, for operating relay 175. Relay 175 locks through the back contact of rotary stepping magnet 178, to ground at the outer upper back contact of relay 174. When relay 171 releases at the end of the first impulse, magnet 177 releases. Relay 173 is slow in releasing and remains operated until after relay 171 has reoperated at the end of the last impulse of the train. Relay 172 is slow in releasing and remains operated during the response of relay 171 to dial impulses. Each succeeding release of relay 171 causes the reoperation of stepping magnet 177, the brushes being thereby raised step by step to the level corresponding to the digit dialed. When relay 173 releases after the reoperation of relay 171 at the end of the last impulse of the train, it closes a circuit including the lower front contact of relay 175 for operating the rotary stepping magnet 178. The operation of magnet 178 advances the brushes into engagement with the first set of terminals in the selected level. Magnet 178 opens the locking circuit of relay 175; and the release of relay 175 opens the operating circuit of magnet 178. If the connected switch connected to the first set of terminals is busy, the test brush 183 encounters ground potential which is extended through the lowermost back contact of relay 174, back contact of magnet 178, and the upper contact of springs 185 to reoperate relay 175. Relay 175 again closes the circuit for operating magnet 178, the brushes being thereby advanced to the next set of terminals. Relay 175 and magnet 178 are in this manner operated and released to advance the brushes until an unguarded set of terminals is encountered; whereupon relay 174 is operated in a circuit from battery through the winding of relay 175, upper contact of spring 185, back contact of magnet 178, winding of relay 174, lower back contact of the 11th rotary step springs 186, to ground at the upper front contact of relay 172. Relay 175 is marginal and does not reoperate in series with relay 174. Relay 174 disconnects the windings of relay 171 from the calling line and extends the connection from the calling line through its front contacts and through brushes 181 and 182 to the line relay (not shown) of the connector switch BC3 to which the selected set of terminals is connected.

The dialing of the last two digits of the called subscriber's number controls the operation of the connector BC3 in usual manner to establish connection with the called line. If the called line is idle, ringing current is transmitted to signal the called station in usual manner. After relays 171 and 172 of selector BS3 release, the connection is maintained under the control of the calling subscriber, holding ground potential in the connector BC3 being connected to the terminal engaged by test brush 183 to hold relay 174 of selector BS3, relays 40 and 57 of the selector repeater SR1, to hold the line finder LF,

and to hold the line and cut-off relay 14 in usual manner.

When the connection is released by the calling subscriber, is holding ground potential is disconnected, causing the release of relays 174, 40, 57 and 14. The release of relay 174 closes a circuit for operating the release magnet 179, the brushes of selector BS3 being thereby restored to normal. The release of relay 40 closes a circuit including back contacts of relays 49, 47 and 42 for operating the release magnet 71 of the selector BS1 and the release magnet 29 of the line finder LF. The brushes of the selector and the brushes of the line finder are thereby restored to normal, the circuits for operating their release magnets being opened at their vertical off-normal springs 67 and 28 when the shafts reach normal. When the called subscriber also releases the connection, the connector BC3 is restored to normal in usual manner.

Assume now that the next digit dialed, after absorption of a first digit 8, is the digit 3; in which case, the brushes of the selector BS1 are advanced to the third level. The release of relay 53 at the end of the last impulse of the train, closes a circuit for operating relays 48 and 83 in parallel. This circuit is traced from the winding of relay 48, through terminals 12 and 13 of terminal strip 78, front contact of relay 84, thence in parallel with the winding of relay 83 through terminals 11 and 14 of terminal strip 78, the outer lower front contact of relay 82, terminal 15 of terminal strip 78, terminal 3 of terminal strip 79, segment 3 of commutator 66, brush 65, lower back contact of relay 86, back contact of release magnet 71, inner lower back contact of relay 53, to ground at a back contact of relay 43. The operation of relay 48 causes the release of relays 55 and 50, thereby releasing the trunk to the main office and the operated selector switches therein. A locking circuit for relays 48 and 83 is closed through the inner lower front contact of relay 83, the upper front contact of springs 67, back contacts of relays 43 and 40, to ground at a front contact of relay 42. Relay 83 closes a circuit for operating relay 86. Relay 86 locks under the control of relays 43 and 40, and closes a circuit for operating the release magnet 71, this circuit being traced from the winding of magnet 71 through the lower front contact of springs 67, outer upper front contact of relay 82, inner upper front contact of relay 83, outer upper front contact of relay 86, through back contacts of relays 43 and 40, to ground at a front contact of relay 42. The operation of magnet 71 restores the brushes to normal, the return of contact springs 67 to their normal position being effective to release relays 48 and 83. When the third digit of the called subscriber's number is dialed, this digit being one of digits 3 to 9, inclusive, the brushes of the selector BS1 are reoperated to select a corresponding level. Relay 87 reoperates as soon as contact 69 closes; and, relay 86 being operated and locked as above described, the release of relay 53 at the end of the last impulse of the train closes the circuit for operating rotary stepping magnet 76, thereby advancing the brushes into engagement with the first set of terminals in the selected level. If the first set of terminals is guarded against seizure, the brushes are further advanced until an unguarded set of terminals is encountered; whereupon relays 49, 41 and 40 are operated as hereinbefore described to seize the terminals and connect the calling line through brushes 61, 62

and 63 to a connector switch BC2 having access to the called line. The dialing of the last two digits of the called subscriber's number effects the operation of the connector switch BC2 to complete the connection with the called line. The connection is under the control of the calling subscriber and release occurs as hereinbefore described.

If the first digit dialed by the calling subscriber is the digit 1, or if a preliminary impulse is accidentally transmitted, the brushes of the selector BS1 are stepped up to the first level. When relay 53 releases after relay 47 has reoperated at the end of the impulse, it closes a circuit for operating the release magnet 71. This circuit is traced from battery through the winding of release magnet 71, lower front contact of the vertical off-normal springs 67, lowermost back contact of relay 85, outer upper back contact of relay 80, terminal 1 of commutator 66 and brush 65, lower back contact of relay 86, upper back contact of release magnet 71, inner lower back contact of relay 53 to ground at a back contact of relay 43. Release magnet 71 locks through the lower front contact of the vertical off-normal springs 67 and upper front contact of magnet 71, to ground at the back contact of relay 43. The operation of magnet 71 causes the brushes to be restored to normal; and, when the shaft reaches normal, the opening of the lower contact of springs 67 causes the operative energization of the lower winding of relay 85 in series with the winding of the release magnet 71. The circuit for operating relay 85 is traced from battery through the winding of the release magnet 71, middle lower front contact of relay 57, lower winding and inner lower back contact of relay 85, front contact of release magnet 71, to ground as above mentioned at a back contact of relay 43. The operative energization of the lower winding of relay 85 effects the closing of a locking circuit through the upper winding and inner upper front contact of relay 85 before the circuit through its lower winding is opened at its inner lower back contact. This locking circuit is traced from battery through the upper winding and inner upper front contact of relay 85, to ground at an upper front contact of relay 42. The opening of the circuit through the lower winding of relay 85 causes the release of magnet 71. The dialing of the second digit 1 causes the reoperation of the selector BS1 and the repeating of the impulses over the trunk to the main office. The brushes of selector BS1 are stepped up to the first level of the bank and, when relay 53 releases after the reoperation of relay 47, it closes a circuit for operating relay 83. This circuit is traced from battery through the winding of relay 83, terminals 11 and 10 of terminal strip 78, lower front contact of relay 85, outer upper back contact of relay 80, terminal 1 of commutator 66 and brush 65, lower back contact of relay 86, upper back contact of release magnet 71, inner lower back contact of relay 53, to ground at a back contact of relay 43. Relay 83 locks through its inner lower front contact, the upper front contact of springs 67, through back contacts of relays 43 and 40, conductor 33, to ground at a front contact of relay 42. Relay 83 closes a circuit for operating relay 86, this circuit including the middle upper front contact of relay 83, and the outer upper back contact of relay 86. Relay 86 closes its locking circuit as hereinbefore traced before its operating circuit is opened, and closes an operating circuit for the rotary stepping

magnet 76. The brushes of selector BS1 are thereupon advanced in the first level of the bank until an idle set of terminals is engaged. If all of the trunks connected to terminals in the first level are busy, the brushes are advanced to the 11th rotary position in which the actuation of springs 68 effects the release of relays 50 and 55 so as to release the trunk to the main office, and effects the transmission of a busy tone to the calling subscriber by connecting the upper winding of the line relay 41 to the busy tone transformer BT in the common miscellaneous alarm and register apparatus MA.

Since the impulses from the digits 11 are repeated over the trunk to the main office, the incoming selector in the main office hunts in the first level of its bank to select a service code selector, and the selected service code selector hunts in the first level while the selector BS1 is hunting for an idle service code selector in the branch office. If the service code selector in the main office encounters an all-trunks-busy condition, a busy tone is transmitted from the main office to the calling subscriber in the branch office, but this does not interfere with the operation of the selected service code selector in the branch office; and, if the service code selector in the branch office is operated responsive to a third digit to complete a connection with a special service trunk as hereinafter described, the trunk to the main office is released.

Upon selection of a unguarded set of terminals 71 in level 1 of selector BS1, relay 49 is operated as above described. Since relay 83 is operated, the operation of relay 49 closes a connection from the winding of relay 41, through the upper winding of relay 40, the inner lower front contact of relay 49, and outer upper front contact of relay 83, to brush 64 of selector S1, so that operation of relays 40 and 41 will be controlled according to the selection made by the service code selector SCS in response to the third digit dialed. The service code selector SCS is similar to the branch office selector BS3. The bank of selector SCS is represented by two sets of terminals, the upper set representing the tenth level having recording completing trunks to a long distance operator connected thereto, and the lower set representing a level which has no trunks connected thereto, selection of this level indicating that the call is to be completed through the main office. Since relay 40 is not operated, relay 41 remains connected to the calling line and the operation of relay 49 closes a bridge across the brushes 61 and 62 for operating the line relay (not shown) of the service code selector SCS. This bridge is traced from brush 61, through the inner upper front contact of relay 41, and outer upper front contact of relay 49, to brush 62. The impulses created by the dialing of the third digit are thus repeated by relay 41 to control the group selecting operation of selector SCS. The brushes of selector SCS are thereupon advanced in the selected level to hunt for an unguarded set of terminals.

Assume first that the third digit dialed is the digit 0, in which case selector SCS trunk hunts in the tenth level and selects an idle recording completing trunk OT1 in this level. The bridge across the brushes 61 and 62 is thereupon extended through brushes 161 and 162 to the selected trunk circuit which operates in usual manner to connect a holding ground potential to the terminal engaged by the test brush 163 and this ground potential is also connected

through brush 164 of selector SCS and brush 64 of selector BS1 to cause the operation of relays 40 and 41. Relay 40 locks as hereinbefore described, causes the release of relay 41, and connects the calling line to the trunk OT1. The holding ground potential connected to brush 163 holds the selector SCS, holds relays 40 and 51, holds the line finder LF, and holds relay 14. When both the calling subscriber and called operator release, the selector SCS, selector repeater SR1, and line finder LF are restored to normal.

If the third digit dialed is one which effects the selection of a level having no trunks connected thereto, the brushes of selector SCS are advanced into engagement with the first set of terminals in the level and the brush 164 engages a terminal which is connected through a resistor 165 to ground, thereby causing the operation of relay 41. Relay 40 is marginal and does not operate. The operation of relay 41 causes the operation of relay 43. Relay 43 locks under control of relays 40 and 42. The operation of relay 43 causes the release of relays 83, 49, 86 and 41. The release of relay 49 opens the bridge across brushes 61 and 62 thereby causing the release of the service code selector SCS, the connection over the trunk to the main office being maintained under the control of relays 41 and 42. When the calling subscriber releases, the selector repeater SR1 and line finder LF are restored to normal as hereinbefore described.

The selector repeater SR1 may be used in a trunking arrangement and numbering plan such that a group of trunks to another office is connected to one of the levels of selector BS1, or a level of this selector may represent a route which can be obtained only by calling the operator. On a call from a restricted service subscriber's station, relay 83 is operated in the manner above described; and upon selection of the level in question, normal post springs 70 are actuated to cause the advance of the brushes to the 11th rotary position to actuate springs 68 and thereby transmit a busy tone to the calling station.

When the line LF is connected through line finder LF to selector repeater SR1 as above described, the operation of relay 42 connects ground through its inner lower front contact, upper winding of relay 88, outer upper back contact of relay 51, and lower back contact of relay 88 to conductor 103 leading to the timing apparatus TA. If at that time relay 135 is normal or as soon thereafter as relay 135 releases, conductor 103 is connected to battery and relay 88 operates. Relay 88 locks in a circuit from battery through the winding of relay 111 in the miscellaneous alarm and register apparatus MA, conductor 164, outer lower front contact of relay 88, outer upper back contact of relay 57, upper winding of relay 88, to ground at a front contact of relay 42. Relay 111, operated by the current in this circuit, closes circuits for operating relays 117 and 144 and for immediately operating start relay 134 if relay 133 is then normal, or for operating relay 134 as soon as relay 133 releases. Relay 117 connects ground to conductor 120 to operate timing relays 121, 122 and 123. The operation of start relay 134 causes the successive operation of relays 131, 132 and 133. The operation of relay 131 causes the operation of relay 135, and relay 135 disconnects battery from conductor 103 and other like conductors. The operation of relay 133, approximately twenty-four seconds after the operation of relay

88, closes a holding circuit for relay 135, causes the release of relay 134, and connects ground to conductor 105 to operate relay 126 and to operate relay 48 in the selector repeater. The release of relay 134 causes the successive release of relays 131, 132 and 133. The circuit for operating relay 48 is traced from conductor 105, through the inner upper back contact of relay 57, middle lower front contact of relay 88, inner upper front contact of relay 55, to the winding of relay 48. The operation of relay 48 causes the release of relays 55 and 50 whereby the trunk to the main office is released. Relay 48 connects ground to brush 93 to guard the trunk against reseizure until the line and release relays (not shown) of the incoming selector in the main office have had time to release so as to prevent false operation of this selector. Relay 48 closes an operating circuit through the upper winding of relay 85. Relay 85 operates, and locks under control of relay 42. The release of relay 55 causes the release of relay 48. With relay 85 operated, and relay 50 released, the release of relay 48 is ineffective to cause the reoperation of relay 55. The release of relay 133, after the operation of relay 48, causes the release of relays 135 and 126 and disconnects ground from conductor 105.

The aforementioned operation of relay 144, upon connection of ground to conductor 130, connects the upper winding of relay 142 to conductor 125 to operate relay 142 as soon thereafter as relays 121 and 122 are normal. When relay 142 operates it locks under control of relay 144. When relay 123 next operates, two to four minutes after relay 142 operates, the connection of ground to conductor 124 causes the operative energization of the lower winding of relay 143. Relay 143 locks through its upper winding under control of relay 144 and connects the upper winding of relay 145 to conductor 103. As soon thereafter as relay 135 is normal, the connection of battery to conductor 103 operates relay 145. Relay 145 locks through its lower winding under the control of relay 144. The next operation of relay 133, approximately twenty-four seconds later, connects ground through the upper front contact of relay 145 to conductor 146, operating relay 141, and through key 115 of the miscellaneous alarm apparatus MA, conductor 102, lowermost back contact of relay 57, inner upper front contact of relay 88, through the upper winding of relay 40 to the winding of relay 41. Relays 40 and 41 are thereby operated a minimum of approximately two minutes and twenty-four seconds after the trunk to the main office is released. The operation of relay 40 disconnects relay 47 from the calling line, causing the release of relays 47 and 42. The release of relay 42 causes the release of relays 83 and 111 and the release of relay 88 causes the release of relays 40 and 41. The selector repeater is thus restored to normal by the operation of release magnet 77 and the line finder LF is restored to normal by the operation of release magnet 29.

The release of relay 42, due to the aforementioned operation of relay 40, disconnects holding ground potential from conductor 33 thereby effecting the release of relay 14; and, if the line circuit of the calling line includes a permanent signal lock-out relay 16, this relay is operated in the manner described in aforementioned patent of T. L. Diamond to prevent the immediate connection of the line to another selector repeater.

If all of the lines to which the selector repeater SR1 may be connected are arranged for per-

manent signal lock-out, conductor 108 is not used and conductor 107 is connected to the inner upper contact of relay 88 instead of to the middle lower contact, thereby causing the operation of relays 40 and 41 at the end of the twenty-four second interval so as to cause release of the line finder, operation of the permanent signal lock-out relay of the calling line, and release of the trunk to the main office.

If conductor 102 becomes permanently grounded due to some trouble condition, relay 141 operates and if conductor 105 becomes permanently grounded, relay 126 operates. The operation of either of relays 126 or 141 connects the upper winding of relay 127 to conductor 125; and relay 127 operates as soon thereafter as timing relays 121 and 123 are normal. Relay 127 locks under control of the operated one of relays 126 and 141. When ground is next connected to conductor 124 by the operation of relay 123, relay 128 is operated by its upper winding. Relay 128 locks under control of relay 126 or relay 141, lights lamp 129, operates relay 135 to disconnect battery from conductors 103, and closes a circuit for operating alarm relay 116. Relay 116 causes the operation of an alarm device and initiation of an alarm call to an operator in the main office.

Referring now to Fig. 9, the trunking plan provides for a total of 800 six-digit subscribers' numbers in the branch office and 10,000 lines in the main office. Numbers from 823200 to 823999 are assigned to the branch office; and numbers from 830000 to 839999 are assigned to the main office. The second to ninth levels of the bank of selector BS are connected directly to connectors BC. Service code selectors are connected to the first level and trunks to an operator are connected to the tenth level of the bank of selector BS. The branch office code consists of two digits, 82, which are both absorbed. The trunk to the main office is released at the end of the second digit; and the selector repeater is arranged to absorb a third digit of any value. The fourth digit then effects the selection of a level in which the selector BS hunts for an idle connector BC having access to the called line.

To arrange the selector repeater SR1 of Figs. 2 and 3 for operation in the trunking plan of Fig. 9, the terminals of terminal strips 78 and 79 are connected as shown in Fig. 9a to secure the desired operation of control relays 80 to 89, inclusive. Calls to "zero" operator are completed as above described for the trunking plan shown in Fig. 8; and if the first digit is any other than 0, 1 or 8, the call is completed through the trunk to the main office in the manner described for such a call when the trunking plan is according to Fig. 8.

If the first digit dialed is 8, relay 81 is operated through segment 8 and commutator brush 65; and the release magnet 77 is operated to restore the brushes to normal. When the operating circuit for relay 81 is opened at the commutator, relay 81 is held and relay 80 operated in a series circuit through the windings of these relays and a back contact of relay 86. When the vertical off-normal springs 67 are restored to normal, relay 65 is operated by the energization of its lower winding in series with the release magnet

77. Relay 85 locks under control of relay 42 and opens its operating circuit to cause the release of magnet 77. If, after absorbing a first digit 8, the next digit dialed is any other than 2, the called subscriber is in some office other than the branch office, and the call is completed over the

trunk to the main office. If, after absorbing a first digit 8, the next digit dialed is the digit 2, relay 84 is operated through segment 2 and commutator brush 65; and the release magnet 77 is again operated to restore the brushes to normal. When the operating circuit of relay 84 is opened by the return of brush 65 to normal, relay 84 is held and relay 82 operated in a series circuit through the windings of these relays, back contacts of relays 43 and 49, and a front contact of relay 42. Relay 82 closes a circuit for operating relay 48 to cause the release of relays 55 and 59 so as to release the trunk to the main office. When relay 55 releases, relay 48 releases. When a third digit is dialed, the brushes of selector BS1 are advanced to the corresponding level; and, when relay 53 releases, relay 83 is operated through commutator brush 65. Relay 83 locks and closes a circuit for operating relay 86. Relay 86 locks and closes a circuit including a front contact of relay 83 for operating release magnet 77 to restore the brushes of selector BS1 to normal. When a fourth digit is dialed, the brushes are advanced to the corresponding one of levels 1 to 9, inclusive; and when relay 53 releases, it closes the circuit for operating the rotary stepping magnet 76 to advance the brushes in this level to select an idle connector BC. When the brushes encounter an unguarded set of terminals, relay 49 is operated closing the circuit for operating relays 49 and 41. The calling line is thereupon connected directly to the associated connector; and the dialing of the last two digits controls the operation of the connector to complete connection with the called subscriber's line.

Consider next the selector repeater SR2 shown in Figs. 4 and 5 in combination with Figs. 1, 6 and 7 arranged as shown in Fig. 12. The selector repeater SR2 is similar to the selector repeater SR1 in Figs. 2 and 3 but it is not arranged for automatic release if connected to a line on which a permanent signal condition exists and the line circuits do not include permanent signal lock-out relays. The selector repeater SR2 also differs from SR1 in that it is arranged for completing special service code calls in response to the dialing of IIX codes or XII codes, the X in either case representing a digit of any numerical value depending upon the character of the call.

The tens and units digits of the reference characters applied to the various elements of selector repeater SR2 are, in so far as possible, the same as those applied to the corresponding elements of selector repeater SR1, thereby facilitating comparison with selector repeater SR1.

The terminals of terminal strips 218 and 219 are connected to each other and to the control relays 280 to 289 as required for the trunking plan and numbering arrangement shown in Fig. 10. Referring to Fig. 10, the trunking plan provides for 700 six-digit subscribers' numbers in an unattended dial office, the office code of which is 262. The master office, to which the dial office is tributary, provides for 10,000 six-digit subscribers' numbers the office code of which is 62. Other dial offices tributary to the master office 62 have office codes, the first two digits of which are 26. The lines in the dial office 262 terminate in the banks of line finders LF and in the banks of connectors. Each line finder is associated with a selector repeater SR2 comprising a numerical selector BS2 and a non-numerical trunk hunting switch TS2 having access to trunks to office 62. The selector BS2 has access in levels 0 and 1 to a group of trunks to the master office

62, these trunks terminating at operators' positions. In levels 2 to 6, inclusive, 8 and 9, the selector BS2 has access to groups of connectors BC, through which local calls are completed. 5 In level 7 the selector BS2 has direct access to trunks to another office, the office code of which is 27.

When a call is initiated at a station B, the calling line is connected by a line finder LF to 10 the associated selector repeater SR2. Relays 247 and 242 are operated, the operation of relay 242 being effective to cause the operation of relays 253 and 255, to connect a holding ground potential to conductor 33, and to operate the start 15 relay 239 of the ringing and tone apparatus RA. The operation of relay 255 causes the operation of relay 245 and the selection of a trunk to the master office. If, when relay 255 operates, the brushes of switch TS2 are connected to an idle 20 trunk, or as soon as the brushes have been stepped into engagement with an unguarded set of terminals, relay 250 operates to prevent the further advance of the brushes and to close the impulse repeating circuits over the conductors of 25 the trunk to prepare the associated incoming selector in the master office for operation in response to dial impulses. The impulse repeating circuits are similar to those established by the operation of relay 50 of selector repeater SR1 as 30 hereinbefore described.

When the calling subscriber dials the first digit of the number of a subscriber's station with which connection is desired, the vertical stepping magnet 275 is operated to advance the brushes of selector BS2 to a corresponding level, and relay 245 repeats the impulses over the trunk to the main office. Relay 257 is operated in response to the first impulse to open the dial tone transmitting circuit, close the talking connection between 40 the calling line and the selected trunk to the master office, and open the connections which would, if no dial impulse were received, initiate the permanent signal release and alarm operations. The normal post springs 269 are actuated to close the 45 circuit for operating relay 287. Relay 287 locks under control of rotary stepping magnet 276. At the end of the first train of dial impulses, relay 253 releases opening the separate impulse repeating circuits over the conductors of trunk T and connecting a supervisory bridge comprising the upper winding of relay 241 across these conductors.

If the first digit dialed is 0, the brushes are advanced to the tenth level; and, when relay 253 55 releases after the last impulse of the train, relay 286 is operated in a circuit through commutator brush 265. Relay 286 locks, closes a circuit for operating relay 248 and a circuit for operating the rotary stepping magnet 276. The operation 60 of relay 248 causes the release of relays 255, 250 and 245 thereby releasing the trunk to the master office. Relay 287 and magnet 276 cooperate to advance the brushes until an unguarded set of terminals are engaged; whereupon the winding of relay 240 is operatively energized in series with the winding of relay 287. Relay 287 is marginal and does not reoperate. The trunk circuit connected to the selected terminals is associated with a trunk to an operator's position, the operation of relay 240 closing the talking connection between the calling line and the selected trunk, and causing the release of relays 247 and 242. After relay 242 releases, relays 240 and 257 are held operated by ground potential connected to the terminal engaged by brush 263 in usual man-

ner. Upon release of the connection by the calling subscriber and also by the operator, the disconnection of holding ground potential from this terminal causes the release of relays 240 and 257, and the release of line and cut-off relay 14. The release of relay 240 closes the circuit for operating release magnet 277 and the selector BS2 is restored to normal.

If the first digit is a digit other than 0, 1, 2 or 4 the called subscriber's line is in the master office or in an office beyond the master office. The brushes of selector BS2 are stepped up to the level corresponding to the digit dialed; and, when relay 253 releases at the end of the train, it closes a circuit for operating relay 243. Relay 243 locks under control of relay 242 and opens the short circuit around resistor 237 thereby inserting this resistor in series with the vertical stepping magnet 275 to prevent the further operation of this magnet in response to dial impulses. The operation of relay 243 disconnects ground from the conductor leading to start relay 239 of the ringing and tone apparatus RA. The brushes remain opposite the selected level, succeeding trains of dial impulses being repeated by relays 247 and 245 over the trunk to the master office to control the completion of the desired connection. When the calling subscriber releases, relays 247 and 242 release and the selector repeater SR2 is thereupon restored to normal.

If the first digit is the digit 2, the brushes of selector BS2 are stepped up to the second level; and, when relay 253 releases, relay 288 is operated in a circuit which includes commutator brush 265. Relay 288 locks under control of relays 286, 243 and 242 and closes a circuit including brush 265 for operating relay 281. Relay 281 closes a circuit for operating release magnet 277. Magnet 277 locks under control of the vertical off-normal springs 267 and relay 257, causes the return of the brushes to normal, and disconnects ground from brush 265, relay 280 being thereupon operated and relay 281 held operated in series, under the control of relay 286. When the brushes reach normal, the release magnet is held in series with the lower winding of relay 285 thereby operating relay 285. Relay 285 locks through its upper winding under control of relays 243 and 242, and opens the operating circuit through its lower winding thereby releasing magnet 277.

When the next digit is dialed after absorbing the digit 2, the brushes are stepped up to the level corresponding to the digit dialed. If this digit is 7, the release of relay 253 after the last impulse of the train, closes a circuit including the inner lower back contact of relay 282, a front contact of relay 288 and brush 265 for operating relay 286. The operation of relay 286 causes the operation of relay 248 and closes the circuit for operating the rotary stepping magnet 276. The operation of relay 248 causes the release of relays 255, 250 and 245 to release the trunk to the master office. The selector BS2 thereupon selects a trunk, in the seventh level of its bank, leading to office 27, and the operation of relay 240 is effective to connect the calling line through brushes 261 and 262 to the selected trunk. Succeeding trains of dial impulses effect the completion of the desired connection in office 27. When the connection is released by the calling subscriber, the selector repeater SR2 is released in the manner hereinbefore described.

If after absorbing the digit 2, the next digit dialed is the digit 1, the brushes are stepped up to

the first level; and, when relay 253 releases, relay 286 is operated through the lower front contact of relay 285, outer lower back contact of relay 282 and commutator brush 265. Relay 286 locks and closes the circuit for operating the rotary stepping magnet 276 to initiate the advance of the brushes to select an idle special service trunk. Upon engagement of the brushes with an unguarded set of terminals, relay 240 is operated to connect the calling line to the associated trunk.

If the next digit dialed, after absorbing the digit 2, is any other than 1, 6 or 7, relay 243 is operated when relay 253 releases. Relay 243 locks under control of relay 242, inserts resistor 237 in series with the vertical stepping magnet 275, and disconnects ground from brush 265. Succeeding trains of dial impulses are repeated by relays 247 and 245 over the trunk to the master office.

If the next digit dialed, after absorbing the digit 2, is the digit 6, the release of relay 253 after the last impulse of the train, closes a circuit for operating relay 284 through commutator brush 265 and front contacts of relays 280 and 288. Relay 284 closes the circuit for operating release magnet 277 to restore the brushes to normal. The operation of magnet 277 disconnects ground from the commutator brush 265, thereby causing the operation of relay 282 and holding relay 284,

in series, under control of relays 286, 243 and 242. When the third digit is dialed, after absorbing 26, the brushes of selector BS2 are again stepped up to the level corresponding to the digit dialed. When relay 253 releases after the last impulse of the train, relay 243 is operated if the digit is any other than 2, the call being completed over the trunk to the master office. If, however, this digit is 2, a circuit is closed through brush 265 for operating relay 286. Relay 286 locks under control of relays 243 and 242 and closes a circuit for operating release magnet 277, disconnects ground from brush 265, and operates relay 248. The operation of relay 248 causes the operation of relay 285 and the release of relays 255, 250 and 245 thereby releasing the trunk to the master office. The release of relay 255 causes the release of relay 248. When the shaft reaches normal, the springs 267 are restored to normal. With relay 286 operated and springs 267 normal, relays 284, 282, 281, 280 and 288 release.

When the fourth digit is dialed, after absorbing 262, the brushes of selector BS2 are stepped up to the level corresponding to the digit dialed. When relay 253 releases after the last impulse of the train, it closes a circuit including the outer upper front contact of relay 286, the lower back contact of relay 284, and the lower front contact of relay 287 for operating the rotary stepping magnet 276. The brushes are thereupon advanced in the selected level until an unguarded set of terminals is encountered, whereupon relay 240 is operated. Relay 240 disconnects the calling line from relay 247 and connects the calling line through brushes 261 and 262 to a connector BC having access to the called subscriber's line. Holding ground potential is connected to the terminal engaged by brush 263 to hold relays 240 and 257 operated, to hold the line finder LF and

to hold the line and cut-off relay 14. The dialing of the last two digits effects the operation of the connector BC to complete connection with the called line. The connection is under the control of the calling station, and release is effected as hereinbefore described.

When the fourth digit is dialed, after absorbing 262, the brushes of selector BS2 are stepped up to the level corresponding to the digit dialed. When relay 253 releases after the last impulse of the train, it closes a circuit including the outer upper front contact of relay 286, the lower back contact of relay 284, and the lower front contact of relay 287 for operating the rotary stepping magnet 276. The brushes are thereupon advanced in the selected level until an unguarded set of terminals is encountered, whereupon relay 240 is operated. Relay 240 disconnects the calling line from relay 247 and connects the calling line through brushes 261 and 262 to a connector BC having access to the called subscriber's line. Holding ground potential is connected to the terminal engaged by brush 263 to hold relays 240 and 257 operated, to hold the line finder LF and

to hold the line and cut-off relay 14. The dialing of the last two digits effects the operation of the connector BC to complete connection with the called line. The connection is under the control of the calling station, and release is effected as hereinbefore described.

If the first digit dialed is a 1, or if a preliminary impulse is accidentally transmitted, the brushes of selector BS2 are stepped up to the first level; and, when relay 253 releases, release magnet 277 is operated through the lower contact of springs 267, outer lower back contacts of relays 285 and 282 and commutator brush 265. Magnet 277 locks independent of brush 265 and causes the return of the brushes to normal. When the vertical off-normal springs 267 are restored to normal, relay 285 is operated and magnet 277 is held operated in series. Relay 285 locks through its upper winding, opens its operating circuit releasing magnet 277, and connects the first level commutator segment to the winding of relay 286. If after absorbing a single impulse, the calling subscriber dials any digit other than 1, the operation of the selector repeater is the same as if this digit were the first digit. But if the second digit dialed is 1, the release of relay 253, at the end of the impulse, closes a circuit through commutator brush 265 for operating relay 286. Relay 286 locks and initiates the trunk hunting operation in level 1 to select an idle trunk to a special service operator. Upon engagement of the brushes with an unguarded set of terminals, relay 240 is operated to connect the calling line to the associated trunk.

If the first digit dialed is the digit 4, the brushes are advanced to level 4, and, when relay 253 releases, relay 281 is operated through both upper back contacts of relay 280 and brush 265. Relay 281 closes a circuit including back contacts of relays 280 and 286 for operating release magnet 277. Magnet 277 locks under control of the vertical off-normal springs 267, causes the return of the brushes to normal, and disconnects ground from brush 265 thereby causing relay 280 to be operated and relay 281 held operated in series under control of relays 286, 243 and 242. When the brushes reach normal, the return of springs 267 to normal causes the operation of relay 285 by the energization of its lower winding in series with release magnet 277. Relay 285 locks through its upper winding, opens its operating circuit to release magnet 277, and connects the winding of relay 286 to the level 1 commutator segment. If the next digit dialed is any other than 1, relay 243 is operated and the succeeding trains of impulses are repeated over the trunk to the main office to control the completion of the desired connection; but if, after absorbing a first digit 4, the next digit dialed is the digit 1, relay 286 is operated and the selector BS2 hunts in level 1 for an idle trunk to a special service operator. When an idle trunk is selected, relay 240 is operated to connect the calling line to the trunk.

Thus a trunk to an operator in the master office may be selected responsive to the dialing of 0, 11, 21 or 41, the connection in each case being held under the joint control of the calling subscriber and operator, by the connection of ground potential to the terminal engaged by brush 263. When the connection is released, the ground potential is disconnected from this terminal to restore the selector repeater SR2 and line finder LF to normal.

If the calling subscriber to which the selector repeater SR2 is connected is a restricted service subscriber, the connection of ground to conductor 35 operates relay 244. If the calling subscriber dials a digit indicating the call is to a subscriber outside of the branch offices, a circuit is closed through commutator brush 265, for op-

erating relay 239. Relay 239 opens its operating circuit, locks under control of relays 243 and 242, closes a circuit for operating relay 286 to initiate trunk hunting, and connects test brush 263 through a back contact of 11th rotary step springs 268 to ground to cause all sets of terminals to test busy. Thereby the brushes are advanced to the 11th rotary position, in which springs 268 are actuated to prevent the further operation of the rotary stepping magnet 276 and to effect the transmission of a busy tone to the calling station.

When a calling line is connected to repeater SR2, the operation of relay 242 connects ground through its inner upper front contact, lower winding of relay 244, lowermost back contact of relay 257, and back contact of relay 244 to conductor 103. As soon thereafter as battery is connected to this conductor by the release of relay 135 of the timing apparatus, and if relay 257 has not operated, relay 244 is operated. Relay 244 transfers its lower winding from conductor 103 to conductor 104, relay 244 being thereby held operated in series with relay 111 of the miscellaneous alarm and register apparatus MA. The operation of relay 111 effects the operation of the timing apparatus TA as hereinbefore described. When the timing relay 133 next connects ground to conductor 105, twenty-four to twenty-eight seconds after the operation of relay 244, relay 248 is operated through the inner upper front contact of relay 244. The operation of relay 248 causes the release of relays 255, 250 and 255, to release the trunk to the main office, and the operation of relay 285. Relay 285 locks independent of relay 248. The release of relay 255 causes the release of relay 248 and relay 285 prevents the reoperation of relay 255. As long as the calling line remains in the calling condition, relays 244 and 111 are held operated. The operation of relay 111 closes a circuit for operating relay 117. Relay 117 connects ground to conductor 150 to start the operation of timing relays 151, 152 and 153 and closes a circuit for operatively energizing the upper winding of relay 119. Relay 119 opens its operating circuit and locks under control of relay 117. When relay 153 operates twenty to thirty minutes after the operation of relay 117, it connects ground to conductor 154 to operate relay 118. Relay 118 locks under control of relay 117 and closes a circuit for operating permanent signal alarm relay 110.

What is claimed is:

1. In a telephone system comprising a main office, a branch office, subscribers' lines and stations in said offices, means at each of said stations for sending trains of directive impulses over the associated line to control the establishing of desired connections, trunks between said offices, a selector repeater in said branch office, local trunks through which connections with called lines in the branch office may be established, and means connecting a calling line in said branch office to said selector repeater, said selector repeater comprising a group selector having a set of brushes and bank of terminals divided into levels, said local trunks being connected to the terminals of said group selector, said selector repeater further comprising a non-numerical trunk-hunting switch the terminals of which are connected to said trunks to the main office, said trunk-hunting switch operable upon connection of a calling line to said selector repeater to hunt for and select an idle one of the

trunks to the main office, means for receiving from the calling line trains of directive impulses corresponding to the office code and numerical digits of the directory listed number of a called subscriber, means for repeating over the selected one of said trunks to the main office the trains of impulses corresponding to all digits of the called subscriber's directory listed number on calls to lines in the main office and for repeating over the selected one of said trunks to the main office only the trains of impulses corresponding to digits of the branch office code on calls to branch office subscribers, means for releasing the trunk to the main office at the end of the train of impulses corresponding to a digit which indicates that the called line is in the branch office, means for advancing and restoring the brushes of said group selector responsive to each train of impulses corresponding to digits of the branch office code other than the last digit of the branch office code, means for advancing the brushes of said group selector to select a set of terminals connected to an idle local trunk in the level corresponding to the last digit of the branch office code if said last digit is one of certain numerical values, means for again restoring the brushes of said group selector to normal at the end of the train of impulses corresponding to the last digit of the branch office code if said last digit is not one of said numerical values, and means for advancing the brushes of said group selector to select a set of terminals connected to an idle local trunk in the level of the bank corresponding to the first train of impulses received after the train corresponding to the last digit of the branch office code if said last digit of the branch office code is not one of said certain numerical values.

2. In a telephone system, a branch office selector repeater comprising an impulse controlled two-motion group selector, local trunks connected to the bank of said group selector, a non-numerical trunking switch, trunks to the main office connected to the bank of said trunking switch, means for advancing the brushes of said group selector to a group corresponding to a train of directive impulses, means for restoring the brushes of said group selector to absorb each of the digits of the branch office code including the last digit of the branch office code if this last digit is a certain numerical value and excluding the last digit of the branch office code if the last digit is a different and certain numerical value, and means for initiating the trunk hunting operation of said group selector in the level selected in response to the last digit of the office code if said last digit is not absorbed and for initiating the trunk hunting operation in the level selected by the next digit dialed after the last digit of the branch office code if said last digit is absorbed.

3. In a branch office selector repeater comprising an impulse controlled group selector having a set of brushes and a bank of terminals giving access to branch office subscribers' lines and comprising a non-numerical switch having access to a group of trunk lines to the main office, said switch operative upon connection of a calling line to said selector repeater to select and seize an idle trunk line to the main office, said selector repeater arranged to repeat trains of impulses incoming from a connected calling line over the selected main office trunk, to absorb the impulses of digits which determine that a call is a local call by advance of the brushes of the group selector to and release of the brushes from the

groups selected responsive to the branch office code, and to release the seized main office trunk responsive to impulses representing the digits of the branch office code, means for absorbing the first train of impulses after the main office trunk is released by advance of the brushes of the group selector to and release of the brushes from the corresponding group, and means responsive to the second train of impulses after the main office trunk is released for selecting the corresponding group and an idle trunk therein through which connection with a called branch office subscriber's line may be completed.

4. In a branch office selector repeater, an impulse controlled group selector comprising a set of brushes and a bank of terminals connected to switches through which connections between subscribers' lines in the branch office may be completed, a non-numerical switch having access to a group of trunks to the main office and operative upon connection of a calling line to the selector repeater to select an idle one of the main office trunks, means responsive to a train of impulses incoming to said selector repeater for repeating the impulses over the selected trunk to the main office, means responsive to a train of impulses representing a digit common to main and branch office subscribers' numbers for operating said group selector to select a group corresponding to the number of impulses in the train, means for absorbing a digit by returning the brushes of the group selector from a selected group to normal, means effective responsive to the train of impulses representing the last digit of the branch office code for releasing the trunk to the main office, means for absorbing the first train of impulses received after release of the main office trunk by advance of the brushes of said group selector to and return of the brushes from the level corresponding to the digit represented by the impulses, and means responsive to the second train of impulses received after release of the main office trunk for operating said group selector to select an idle branch office switch in the group corresponding to said second train of impulses.

5. In a branch office selector repeater comprising an impulse controlled group selector having a set of brushes and a bank of terminals connected to trunks giving access to branch office subscribers' lines and comprising a non-numerical switch having access to a group of trunk lines to the main office, said switch operative upon connection of a calling line to said selector repeater to select and seize an idle trunk line to the main office, said selector repeater arranged to repeat trains of impulses from a connected calling line over the selected main office trunk, to absorb the impulses of digits which determine whether the call is a local or a main office call by advance of its brushes to and release of its brushes from the groups corresponding to said digits, to release the seized main office trunk and select a trunk in the group giving access to a called subscriber's line in the branch if said digits indicate the called subscriber's line is in the branch office, and means for automatically releasing the seized trunk to the main office, said means effective a predetermined interval of time after connection of a calling line to said selector repeater if no impulses are received prior to the expiration of said interval.

6. In a branch office selector repeater, an impulse controlled group selector comprising a set of brushes and a bank of terminals connected to

branch office switches through which connection between branch office subscribers may be completed, a non-numerical switch operative upon connection of a branch office subscriber's line with said selector repeater for selecting an idle trunk to the main office, means responsive to trains of impulses incoming to said selector repeater for repeating the impulses over the selected main office trunk, means for absorbing trains of impulses common to main and branch office subscribers' numbers by advancing and restoring the brushes of the group selector responsive to each such train of impulses, means responsive to a train of impulses representing the last digit of the branch office code for releasing the trunk to the main office, means responsive to a train of impulses representing a digit of a branch office subscriber's number other than a digit common to branch and main office subscribers' numbers for operating said group selector to select a set of terminals in the corresponding level, and means for releasing a selected main office trunk if no impulses are received within a predetermined interval of time after connection of a line to the selector repeater.

7. In a branch office selector repeater comprising an impulse controlled group selector through which connections between branch office subscribers' lines may be completed and a non-numerical switch for selecting an idle trunk to the main office responsive to connection of a branch office subscriber's line to the selector repeater, means for releasing the trunk to the main office if no impulses are received within a predetermined interval of time after seizure of a main office trunk.

8. In a telephone system comprising a branch office and a selector repeater therein according to claim 5, lines each having a line relay and a line-lock-out relay associated therewith, the operation of a line-lock-out relay being effective to render the associated line relay ineffective to initiate a call, said selector repeater comprising relay means operative upon connection of a calling line to said selector repeater for maintaining the connection, means effective if no dial impulses have been received before the end of said predetermined interval of time for opening the connection between the calling line and said relay means thereby to effect the opening of the connection between the calling line and the selector repeater and the operation of the line-lock-out relay of the calling line.

9. In a telephone system comprising a branch office and a selector repeater therein according to claim 5, lines each having a line relay, each of certain of said lines also having a line-lock-out relay, the operation of a line-lock-out relay being effective to render the associated line relay ineffective to initiate a call, said selector repeater comprising relay means operative upon connection of a calling line to said selector repeater for maintaining the connection, and means in said selector repeater effective a predetermined interval of time after said release of a main office trunk for opening the connection between the calling line and said relay means thereby to effect the opening of the connection between the calling line and the selector repeater.

10. In a telephone system comprising a branch office and a selector repeater therein according to claim 7, subscriber's lines, means comprising a line relay for effecting the connection of a line to said selector repeater, means comprising a line-lock-out relay for disconnecting said line 70

from said line relay, means in said selector repeater effective upon connection of said line thereto for maintaining said connection, and means effective if no impulses have been received 5 from the calling line before the end of said predetermined interval of time for operating said line-lock-out relay and for effecting the disconnection of said line from said selector repeater.

11. In a telephone system comprising a branch office and a selector repeater therein according to claim 7, a calling line, means connecting said line to said selector repeater, means in said selector repeater for maintaining said connection, and means effective a predetermined interval 15 after the release of said trunk for disconnecting said line from said selector repeater.

12. In a telephone system comprising a main office and a branch office, a selector repeater in the branch office, said selector repeater comprising an impulse controlled group selector through which connections between branch office subscribers' lines may be completed and a non-numerical switch for selecting an idle trunk to the main office responsive to connection of a branch office subscriber's line to the selector repeater, a calling line, means connecting said line to said selector repeater, means in said selector repeater for maintaining said connection, and means effective if no impulses are received from said calling 30 line within a predetermined interval of time after connection of said line and selector repeater for disabling said means for maintaining the connection and for releasing the trunk to the main office.

13. In a telephone system comprising a main office, a branch office, subscribers' lines and stations in said offices, including restricted service lines in said branch office, means at each of said stations for sending trains of directive impulses 40 over the associated line to control the establishing of desired connections, trunks between said offices, a selector repeater in said branch office and means connecting a calling line in said branch office to said selector repeater, said selector repeater comprising a group selector having a set of brushes and bank of terminals divided into levels, groups of local trunks through which connections with called lines in said branch office may be established, said local trunks connected to the terminals of the bank of said group selector, said selector repeater further comprising a non-numerical trunk-hunting switch, the terminals of which are connected to the trunks to the main office, said trunk-hunting switch being operative upon connection of a calling line to said selector repeater to hunt for and select an idle one of the trunks to the main office, said selector repeater further comprising means for receiving from the calling line trains of directive 50 impulses corresponding to the office code and numerical digits of the directory listed number of a called subscriber, means for repeating over the selected one of said trunks to the main office the trains of impulses corresponding to all digits of the called subscriber's directory listed number on calls completed through the main office and for repeating over the selected one of the trunks to the main office the trains of impulses corresponding to digits of the branch office code of the directory listed number of branch office subscribers, means for releasing the trunk to the main office at the end of the train of impulses corresponding to a digit which indicates that the called line is in the branch office, and means effective if the calling line is a restricted service

65

60

65

70

75

line for causing the release of the trunk to the main office in response to the train of impulses corresponding to a digit which indicates that the called subscriber's line is not in the branch office.

14. In a dial telephone system, a branch office selector repeater comprising an impulse controlled two-motion group selector switch and a non-numerical trunking switch, an operator's position, a group of trunks connecting the first level of said selector switch to said operator's position, said trunk group being selectable in response to the dialing of a plurality of codes, the first two digits of which are 11 or a particular digit other than 1 followed by the digit 1, means in said selector repeater responsive to dial impulses for registering the first digit of said codes and returning the brushes to normal, and means for trunk hunting in said trunk group in response to the second digit of said codes to select an idle trunk in said group.

15. In a telephone system, a branch office selector repeater comprising an impulse controlled two-motion group selector switch having a set of brushes and a bank of terminals, the terminals in a plurality of levels of said bank connected to groups of switches through which connections between subscribers' lines in the branch office may be completed and the terminals in the first and tenth levels of said bank connected to trunks to an operator, a non-numerical switch having access to trunks to the main office and operative upon connection of a calling line to the selector repeater to select an idle one of the main office trunks, means responsive to a train of impulses incoming to said selector repeater for repeating the impulses over the selected trunk to the main office, means responsive to a train of impulses in-

coming to said selector repeater for operating said group selector to select a level corresponding to the number of impulses in the train, means responsive to the selection of any one of a plurality of levels including the first level by said selector switch in response to a first train of impulses for restoring the brushes to normal, means responsive to a second train of impulses incoming to said selector repeater for operating said group selector to select a level corresponding to the number of impulses in the train, means responsive to the selection of either the first or the tenth level responsive to said second train of impulses for causing the release of the trunk to the main office and selection of an idle one of the trunks to an operator.

16. In a dial telephone system comprising a plurality of central offices including a main and a branch office, a branch office selector repeater comprising a dial impulse controlled two-motion group selector switch and a non-numerical trunking switch, trunks to the main central office connected to the bank of said trunking switch, local trunks connected to one or more levels of said group selector switch, trunks to another central office connected to a level of said group selector switch and selectable in response to the dialing of a particular two-digit code, means in said selector repeater responsive to dial impulses for recording the first digit of said code and returning the brushes of said selector switch to normal, and means in said selector repeater responsive to dial impulses for selecting the level corresponding to the second digit of said code and for selecting an idle trunk in the group to said other central office.

HENRY HOVLAND.
